UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

POURING SHEET

Application filed January 26, 1927, Serial No. 163,683. Renewed May 31, 1930.

This invention relates to means for mounting a pouring sheet in a stereotype plate casting mold in such manner that the sheet itself may be formed of rigid material having a thickness considerably greater than that of the usual pouring sheets. Such a thick sheet cannot be carried by the mat carrying clips and is so constructed of course that it will not have to be flexed with the matrix. 10 Another feature of the invention is the fact that on account of the thickness of the pouring sheet its lower edge can be thinned down to receive the upper edge of the matrix behind it and still the pouring sheet can lie flat against the casting box so as to engage it all the way from the matrix to the top. This provides more efficient cooling for the tail of the plate.

Other objects and advantages of the invention will appear hereinafter.

Reference is to be had to the accompanying drawings in which

Fig. 1 is a plan of a curved stereotype plate casting mold with the back shown in horizontal section illustrating a preferred embodiment of this invention and showing the mold open;

Fig. 2 is a similar view in plan and showing the mold closed;

Fig. 3 is a radial sectional view of the bottom of the pouring sheet and top of the matrix showing how they fit together; and

Figs. 4, 5 and 6 are plans of a casting box with another form of this invention applied thereto showing the parts in three different positions.

In Figs. 1, 2 and 3 I have shown the invention as applied to a mold comprising a cylinder or core 10 and a casting box or back 11 in which these two parts are separated as shown in Fig. 1 for the purpose of delivering the casting and allowing for replacement of the matrix if desired. The matrix is mounted on the usual clips 12 which are turned in the usual way to strip the matrix from the casting and separate it from the back. Ordinarily the pouring sheet has been of thin flexible material and carried by these clips 12. In the present case, I provide a pouring sheet 3 of comparatively heavy material

and consisting of a thin sheet which retains its rigidity when supported at its two edges. The pouring sheet is located, of course, at the top of the matrix to receive the metal poured in and protect the mold itself from the overheating and erosion caused by the running of the hot metal down the back. 55

Instead of supporting the pouring sheet by the clips 12 I mount it on a pair of supports 4 located substantially diametrically opposite each other. These supports extend out in opposite directions and each one is carried by a guide-pin 5 arranged tangentially. In this form of the invention the guide-pins are guided in lugs 6 extending from a stationary part of the frame 7. Each pin 5 is provided with a spring 8 and a head 9 behind it, the spring being adapted to pull the supports 4 back into contact with the outer lugs 6 when free to do so and the springs yielding as shown in Fig. 2 to permit the movement of the supports 4 further in toward the cylinder. This brings the pouring sheet into operative position. 70

As stated above, the pouring sheet is provided with a thin portion 2 at the bottom having a recess 1 and a shoulder at the top of the recess. When the pouring sheet is up against the back 11, this recess 1 is just thick enough to receive the upper edge of the matrix under it to form a tight joint to prevent the metal getting in behind the matrix. At the same time, the shoulder is shown as abrupt. The back of the pouring sheet comes into contact with the back of the casting box at this point and engages it throughout its area above this line. In this way, the usual air space between the pouring sheet and the back is avoided and the back and pouring sheet co-operate to conduct the heat away from the casting through an all-metal path. This affords a more rapid cooling of the tail of the casting than has been the case heretofore. 75

In operation, assuming the mold to be open 95 as shown in Fig. 1, when the back comes up toward the cylinder the matrix is set back into the concavity of the casting box, by means well known, through the operation of the clips 12. As the back continues to move 100

toward the cylinder a pair of lugs 25 connected with the back engage the extreme ends of the pins 5 and by the time the back is entirely closed, the supports 4 are forced forward to the position shown in Fig. 2 and the pouring sheet is let into the back and into engagement with it as shown in Fig. 3. It also overlaps the matrix at the bottom as just described.

- 10 In the form shown in the second sheet of drawings, a similar pouring sheet 3 is illustrated formed in the same way but operated a little differently as the casting box 11 itself carries the pins 5 by means of lugs 26 on the casting box. The pouring sheet is carried by supports 24 similar to the supports 4 and the pins 5 are secured to them in the same way and the same springs 8 are used. In this case the mold is shown entirely open in Fig. 4 and in Fig. 5 it is shown entirely closed.

When the pouring sheet reaches the position shown in Fig. 6, it is kept from further movement towards the cylinder by being brought into engagement with the front of two stationary lugs 30. The mat bar is shown in a cocked position in Fig. 6 and in the fully closed position in Fig. 5. These mat bars are actuated by the lugs 28 on top 30 of the cylinder as shown in Fig. 4. From this it is to be seen that the pouring sheet cannot get any closer to the cylinder than it is permitted to do by the mat bars. As the mold begins to open, the parts pass through 35 the position shown in Fig. 6 in which the pouring sheet is first separated from the casting box as that moves back, and afterwards moves back with it as shown in Fig. 4 to final open position.

- 40 It will be seen that, with this invention, the pouring sheet can be made practically inflexible and can be carried in a positive manner and set back into the casting box accurately by the operation of the machine. 45 The matrix may be lowered into or withdrawn from the casting box, either by reaching down in front of the pouring sheet and pushing the matrix back and up into the space between the pouring sheet and the box, 50 or by raising the entire clip if preferred. The pouring sheet is more durable than those heretofore employed. It presses back against the mold so that the heat is conducted away from it more rapidly than has been the case heretofore and it is carried rigidly and positively as above stated.

Although I have illustrated and described only two forms of the invention I am aware of the fact that other modifications can be 60 made therein by any person skilled in the art without departing from the scope of the invention as expressed in the claims. Therefore, I do not wish to be limited to all the details of construction herein shown and described, but what I do claim is:—

1. In a stereotype printing plate casting box, the combination with the back and core, of a rigid pouring sheet located between the back and core, a pair of guide-pins located parallel to the direction of separation of the back and core, and supporting the opposite ends of the pouring sheet; and springs upon them for normally forcing the pouring sheet toward the back.

2. In a stereotype plate casting mold, the combination with a casting box and cylinder, of a pouring sheet between the two formed of rigid material and of a general semi-cylindrical form, supports at its straight edges, pins connected with said supports, said pins being slidable in the direction of the movement of the back, springs on the pins for forcing them tangentially, and means for engaging the pins as the back moves up and moving the pins and pouring sheet to casting position.

3. In a stereotype plate casting mold, the combination with the cylinder and back, of a pouring sheet, a pair of guide-pins connected with the opposite ends of the pouring sheet for supporting it, means on the back for carrying and guiding said pins, and means on the cylinder for engaging the ends of the pins as the back and cylinder are brought into casting position and forcing the pouring sheet back into the casting box to be seated against the same.

4. The combination with a casting box and means for supporting a matrix therein, of a pouring sheet and means carried by the back, independent of the matrix supporting means for carrying the pouring sheet.

5. In a stereotype plate casting mold, the combination with a casting box and means for supporting a matrix therein, of reciprocal means independent of the matrix supporting means for carrying a pouring sheet in position to overlie the edge of the matrix when the mold is closed for casting.

In testimony whereof I have hereunto affixed my signature.

HENRY A. WISE WOOD.
